UNITED STATES PATENT OFFICE

156,483

PORTABLE REFRIGERATOR

Ille S. Carrington, Burbank, Calif.

Application January 3, 1949, Serial No. 11

Term of patent 7 years

(Cl. D67—3)

To all whom it may concern:

Be it known that I, Ille S. Carrington, a citizen of the United States, and a resident of the city of Burbank, in the county of Los Angeles and State of California, have invented a new, original, and ornamental Design for a Portable Refrigerator, of which the following is a specification, reference being had to the accompanying drawings, forming part thereof, in which:

Fig. 1 is a perspective view of a portable refrigerator, showing my new design;

Fig. 2 is a side view; and

Fig. 3 is a rear view of the refrigerator.

I claim:

The ornamental design for a portable refrigerator, as shown.

ILLE S. CARRINGTON.
